SAFETY WRENCH FOR FAUCETS AND LIKE VALVES

Abram W. Wheaton, Maplewood, N. J., assignor to
 A. W. Wheaton Brass Works, Newark, N. J.,
 a corporation of New Jersey

Application October 5, 1934, Serial No. 746,992

7 Claims. (Cl. 137—162)

This invention relates to safety wrenches for operating self-closing faucets and like valves.

Faucets of the self-closing type are, for many uses, frequently arranged to be actuated by a detachable wrench, means being sometimes provided for so holding the wrench in faucet valve opening position that the faucet remains open against the pressure of its self-closing means until the wrench is manually released. Such wrench operated self-closing faucets are commonly employed for dispensing gasoline, oil or other inflammable liquid from supply reservoirs, tank wagons and the like; and in such use, it is of great convenience to provide an operating wrench which may be stopped 10 or held in faucet valve opening position, especially when continuously delivering a considerable quantity of liquid at one time. Even when the wrench is not designed to be locked and held in valve opening position, the operator, in order to avoid necessity of standing by and manually holding the same in such position, will often secure the wrench therein by tying or wedging the same in some manner. There is an objection however to locking, tying or wedging the operating wrench of such faucets in valve opening position, since in the event of fire, access to the wrench for releasing the same may not be possible, and consequently the faucet would remain open under such conditions, with risk not only of loss of the liquid dispensed, but of greater loss through spread of the fire by the feeding of inflammable material thereto.

The present invention has for its principal object to provide a wrench for operating self-closing faucets which if locked, tied, wedged or otherwise held in valve opening position, will, nevertheless, when subjected to abnormal heat, at once yield to closing movement of the valve regardless of its said locked or held condition.

Another object of the invention is to provide, in connection with a wrench designed to be locked or engaged to the faucet in its valve opening position, a normally rigidly supported socket member adapted to yield rotatively under the influence of abnormal heat.

Other objects of this invention, not at this time more particularly enumerated, will be understood from the following detailed description of the same.

An illustrative embodiment of this invention is shown in the accompanying drawing, in which:—

Fig. 1 is in part an elevational and in part a sectional view of a self-closing faucet showing the novel safety wrench as operatively applied thereto for manipulation of the faucet; Fig. 2 is in part

a top plan and in part a horizontal sectional view of the same; and Fig. 3 is a view, similar to that of Fig. 1, but showing the safety wrench as released by abnormal heat.

Fig. 4 is a fragmentary longitudinal section of the wrench, taken on line 4—4 in Fig. 2, but drawn on an enlarged scale; and Fig. 5 is a fragmentary top plan view of the socketed end of the wrench.

Similar characters of reference are employed in the above-described views, to indicate corresponding parts.

Referring to the drawing, the reference character 1 indicates a faucet body having an interior chamber 2, into which leads an intake portion 3 and from which leads an outlet portion 4. Intermediate the intake and outlet, at the lower part of said faucet body 2 is an annular valve-seat shoulder 5. The upper part of said faucet body is provided with a housing 6, within which is seated a closing spring 7 which surrounds a valve stem 8 so as to thrust upon a valve member 9, to hold the latter yieldably to its seat 5, and thus in normal closed condition. The faucet body is further provided with a horizontal laterally disposed off-set portion 10, provided with suitable bearings 11 in which is journaled a cam shaft or spindle 11, one end of which projects exteriorly through a suitable stuffing box gland 12, and terminates in a squared end 13 adapted to receive operative application thereto of a wrench usable for manually opening the valve member 9 against the closing pressure of the spring 7. Affixed to said shaft or spindle 11 is a lift-cam 14, which enters a slot 15 in the valve stem 8, thereby operating, when the shaft or spindle is properly turned, to lift the stem 8 and valve member 9 into open relation to the valve port P defined by the valve-seat shoulder 5.

The above-described faucet structure has been set forth for the purpose of illustration, and merely discloses one specific form of self-closing valve with which the safety wrench of this invention may be used as an actuating means, and consequently it will be understood that said wrench is not limited for use with the particular faucet structure described, but is equally applicable to any type or design of faucet or valve having a wrench receiving mechanism, and thus being adapted for wrench actuation.

In the faucet above described and illustrated in the accompanying drawing, the faucet body is provided with a stop-projection or nosing 16, engageable by a portion of the wrench, after the same has been moved to valve opening position, to thereby lock or hold said wrench in such position.

sition. Wrenches designed and arranged for co-operation with such locking or holding means are now well known, and the novel safety features of the wrench constructed in accordance with the present invention are shown as embodied in a wrench of such character; it will, however, be obvious that the safety features of the wrench may be applied to any type or kind thereof, whether provided with such or similar lock stop engaging means or not, since these safety features are operative in accordance with their desired functions in a wrench which is, in any manner, tied, wedged or otherwise blocked in valve opening position.

15 The illustrative form of valve operating wrench shown in the accompanying drawing, comprises a head-piece 17 provided with a transverse cylindrical bore 18 extending therethrough. At its inward end said head-piece 17 is provided with 20 a pair of vertically spaced horizontal perforate ears 19, through which extends and by which is supported a pintle 20. Journaled on this pintle 20 is a handle or lever portion 21, which is thus pivotally associated with said head-piece 17 so as to be capable of swinging movement 25 relative thereto in horizontal plane, while nevertheless being capable of transmitting the necessary turning movement to said head-piece. Connected with the handle or lever portion 21, preferably as an integral part thereof, is a laterally extending stop projection or arm 22. Carried by said head-piece 17 is a wrench socket member 23 having a cylindrical shank 24 to fit and engage in the bore 18 of said head-piece. Said socket 30 member 23 is provided with a square cavity or socket 25 to fit upon and thus receive the square end 13 of the spindle 11 of the faucet valve operating means. Means are provided capable of breaking down or yielding under heat and yet, 35 under normal cool conditions, serving to rigidly and unyieldingly secure said socket member to the head-piece of the wrench. Such means comprises one or more pins or dowels 26 of fusible metal, which are disposed in aligned openings or passages 27 and 28 with which the socket member and head-piece of the wrench are respectively provided. Preferably such aligned openings or 40 passages 27 and 28 extend in the shank 24 and head-piece 17 radially or laterally to the axis of rotation of the latter when the wrench is moved for applying valve operating rotation to the spindle 11 of the valve operating mechanism, whereby 45 the pin or dowel 26 acts as a key or lock to normally prevent rotative movement of the socket member 23 relative to the head-piece 17. While, in the drawing, three pins or dowels 26 are shown in such arrangement, it will be obvious that such number thereof may be more or less as may be desired in any given case.

50 In use, when the wrench is operated to open the faucet valve against the pressure of spring 7, the handle 21 is swung laterally to bring the stop-projection or arm 22 beneath the nosing 16, thus locking the wrench to hold or maintain the spindle 11 of the valve operating mechanism turned to valve opening position, and thereby the faucet in continuous liquid discharging condition. In the event of fire in the vicinity of the thus open faucet, the heat emanating therefrom has, directly and by conduction through the metal of the head-piece of the wrench, access to the pins or dowels 26 of fusible metal. Owing to the low melting point of the metal composing the pins or dowels 26, heat thus applied thereto will 55 quickly melt or liquefy the same, so that they will

very quickly break down from their normal solid and rigid condition and thus lose their holding or keying effect between the socket member and head-piece of the wrench, with the consequence that pressure of the spring 7, acting through the valve 8-9 and cam 14 and tending to rotate the spindle 11 will no longer be resisted for the reason that the socket member 23, not being held against turning in the head-piece 17 by the pins or dowels 26, will rotate relative to the immovably locked head-piece, and consequently the valve 9 will quickly move into closed relation to the port P, and the faucet will therefore quickly be automatically closed against further discharge of liquid therethrough.

15 I am aware that various changes could be made in the specific form of wrench above set forth and many apparently widely different embodiments of this invention could be made without departing from the scope thereof. It is therefore intended 20 that all matter contained in the above description or shown in the accompanying drawing shall be interpreted as illustrative and not in a limiting sense.

I claim:

1. An attachable wrench for operating a self-closing valve comprising a head-piece, a valve spindle engaging member capable of rotation relative to said head-piece, and fusible means for normally keying said member against rotation 30 relative to said head-piece whereby upon melting of said keying means said member may so rotate under valve closing movement of said valve spindle.

2. An attachable wrench for operating a self-closing valve comprising a handle member, a head-piece carried by said handle member, said head-piece having a transverse bore, a valve spindle engaging member having a shank journaled in said bore, and fusible means for normally keying said shank against rotation in said bore and thus said engaging member against rotation relative to said head-piece whereby upon melting of said keying means said engaging member may so rotate under valve closing movement of said valve 45 spindle.

3. An attachable wrench for operating a self-closing valve comprising a handle means having a portion provided with a transverse bore, a valve spindle engaging member rotatably mounted in 50 said bore, and fusible means for normally keying said member against rotation in said bore whereby upon melting of said keying means said member may so rotate under valve closing movement of said valve 55 spindle.

4. An attachable wrench for operating a self-closing valve comprising a handle means having a portion provided with a transverse bore, a valve spindle engaging socket member having a shank rotatably mounted in said bore, and dowel means 60 of fusible metal normally locking said shank against rotation in said bore whereby upon melting of said dowel means said shank may turn in said bore to permit rotation of said socket member under valve closing movement of said valve 65 spindle.

5. An attachable wrench for operating a self-closing valve comprising a handle means, a head-piece carried by said handle means, said head-piece having a transverse bore, a valve spindle 70 engaging socket member having a shank rotatably mounted in said bore, said head-piece and shank having alignable openings extending from their meeting surfaces, and key means of fusible metal disposed in said alignable openings to normally 75

lock said shank to said head-piece to prevent rotation of said socket member relative to said head-piece whereby upon melting of said key means said socket member is freed to rotate relative to said head-piece under valve closing movement of said valve spindle.

6. An attachable wrench for operating a self-closing valve comprising a head-piece and a valve spindle engaging member carried thereby, a handle member pivoted to said head-piece for movement laterally with respect to the plane of normal operating movement of said handle, said handle member having a stop portion engageable with a suitable stop to hold the valve operating spindle in valve opening position, said valve spindle engaging member being capable of rotation relative to said head-piece, and fusible means for normally keying said spindle engaging member against rotation relative to said head-piece whereby upon melting of said keying means said member may so rotate under valve closing movement of said valve spindle.

7. An attachable wrench for operating a self-closing valve comprising a head-piece and a valve spindle engaging member carried thereby, a handle member pivoted to said head-piece for movement laterally with respect to the plane of normal operating movement of said handle, said handle member having a stop portion engageable with a suitable stop to hold the valve operating spindle in valve opening position, said valve spindle engaging member having a cylindrical shank, said head-piece having a transverse bore to receive said shank to rotatably relate said spindle engaging member thereto, and dowel means of fusible metal normally locking said shank against rotation in said head-piece whereby upon melting of said dowel means said shank may turn in said bore to permit rotation of said spindle engaging member relative to said head-piece under valve closing movement to said valve spindle.
